TRANSMISSION CONTROL IN TWO-WAY
SIGNALING SYSTEMS

Bjorn G. Bjornson, Brooklyn, N. Y., assignor to
Bell Telephone Laboratories, Incorporated,
New York, N. Y., a corporation of New York

Application January 27, 1932, Serial No. 589,197

8 Claims. (Cl. 179—170)

This invention relates to two-way signal transmission circuits, and particularly to the signal-controlled circuits employed therewith for suppressing echoes and preventing singing. 5 An object of the invention is to improve the operation characteristics of a long two-way signaling system comprising over at least a portion of its length four-wire circuits and employing therewith signal-controlled apparatus 10 for suppressing echoes and preventing singing.

To obtain proper operation of long two-way signaling systems, for example, long four-wire voice frequency or carrier telephone circuits, it has been found necessary in the past to utilize in connection therewith signal-controlled apparatus for effectively disabling one of the associated two-wire paths while signal transmission is taking place over the other, so as to prevent echo currents or reflected currents from 15 being transmitted back to the transmitting end of the system and causing a disturbance or singing. The disabling apparatus usually comprises means, such as an amplifier-rectifier control circuit, for diverting a portion of the signaling current from one path and utilizing it 20 to control the open-circuiting or short-circuiting of the oppositely directed path, or to control the operation characteristics of an amplifier in the oppositely directed path.

30 In certain circuits of the prior art, these signal-controlled devices, or echo suppressors as they are commonly called, one of which is associated with each two-wire path, are located at some intermediate station, for example, at a midway point. Such an arrangement has the disadvantage that it may prevent the subscriber who starts to talk in one direction from getting immediate control of the circuit after it has been used by the subscriber talking in the other 35 direction. This is due to the fact that, owing to the time interval which it takes for a wave to be transmitted from the echo suppressor associated with one side of the circuit through the terminal to the point at which the oppositely-directed circuit is disabled, the echo suppressor must be provided with hang-over means to maintain the line disabled for a certain length of time after the first talker has finished talking. In other circuits of the prior art this 40 difficulty has been eliminated by locating the two units of the echo suppressor respectively at or near the ends of the four-wire circuit. The latter arrangement, the so-called terminal echo suppressor, enables a substantial reduction in 45 the breaking time to be obtained. In the cir-

cuits of the prior art the terminal echo suppressors have been of the "receiver" type, the suppression unit at each terminal comprising a suppressor responsive to signals in the incoming two-wire circuit to disable the outgoing two-wire circuit and means responsive to signals in the outgoing two-wire circuit to disable the suppressor at the same terminal. 5

One embodiment of the present invention relates to a two-way signaling system employing 10 terminal echo suppressors of what may be called the "sender" type. In this system the suppression device at each terminal comprises a suppressor responsive to signals in the outgoing two-wire circuit to disable the incoming two-wire circuit, and means responsive to signals in the incoming circuit to block the suppressor at the same terminal. 15

A feature of the invention is the provision in a two-way signaling system employing terminal 20 echo suppressors and automatic volume control circuits, of switching means for preventing false operation of the volume control circuits by the suppressors.

In a modification of the invention particularly 25 applicable to a two-way radio or cable telephone circuit, the echo suppression apparatus comprises an echo suppressor unit of the "sender" type and an echo suppressor unit of the "receiver" type both located at the same terminal. 30

The exact nature and the advantages of the 35 circuits of the invention will be clear from the following detailed description thereof when read in connection with the accompanying drawings in which:

Fig. 1 shows schematically one four-wire channel of a multiplex carrier cable telephone system employing the "sender" type of echo suppressor embodying the invention;

Fig. 2 shows schematically one four-wire channel of a multiplex carrier cable telephone system employing the "receiver" type of terminal echo suppressor; and

Fig. 3 shows schematically a long four-wire toll telephone circuit employing a "sender" type 45 of terminal echo suppressor in connection with one side of the four-wire circuit and a "receiver" type of terminal echo suppressor in connection with the other side of the four-wire circuit.

Fig. 1 shows schematically a multiplex, four-wire carrier cable system for transmitting telephonic signals in either direction between a two-way telephone circuit L_1 incoming at a west station A and a two-way telephone circuit L_2 55

- incoming at an east station B. Only one carrier channel for each direction has been illustrated in detail.
- The west to east, one-way transmission path 5 EA forming one carrier channel between stations A and B includes at station A a volume control device 1, a modulator M_1 and associated carrier frequency oscillator O_1 , and a band pass filter 2, and at station B a band pass filter 3, 10 a demodulator DM_1 and associated carrier frequency oscillator O_2 and a compensating volume control 4. The east to west, one-way transmission path WA forming the second carrier channel connecting stations B and A includes 15 at station B a volume control device 5, a modulator M_2 and associated carrier frequency oscillator O_3 and band pass filter 6 and at station A a band pass filter 7, a demodulator DM_2 and associated carrier frequency oscillator O_4 , and 20 a compensating volume control device 8. The input of the west to east transmission path EA and the output of the east to west transmission path WA are connected in substantially conjugate relation with each other and in energy 25 transmitting relation with the east end of the telephone circuit L_1 in well-known manner by means of the hybrid coil H_1 and associated balancing network N_1 . Similarly, the input of the east to west transmission path WA and the output of the west to east transmission path EA 30 are connected in substantially conjugate relation with each other and in energy transmitting relation with the west end of the telephone circuit L_2 in well-known manner by means of the 35 hybrid coil H_2 and associated balancing network N_2 . In addition to the apparatus mentioned the west to east transmission path EA and the east to west transmission path WA would contain a number of one-way amplifying devices 40 located at various points therealong for giving the required degree of amplification to the speech frequency signals or the signal modulated carrier as determined by the attenuation characteristics of these paths between the stations 45 A and B.
- The volume control device 1 in the transmission path EA at station A, and the volume control device 5 in the transmission path WA at station B, are utilized to maintain the volume 50 level of the telephonic currents transmitted to modulators M_1 and M_2 respectively constant within definite limits irrespective of a wide range of volumes in the source of signals. This is desirable to insure proper signal volume at the 55 receiving end of the system and to insure proper operation of the echo suppressors associated with the transmission path, to be described. The compensating volume control device 8 in the output of the transmission path WA at station A and the corresponding compensating volume control device 4 in the output of the transmission path EA at station B, are utilized to 60 make an adjustment in the volume level in these paths which is the inverse of that produced in the path transmitting signals, so that the transmission equivalent over the loop circuit comprising both paths EA and WA is not changed by the volume adjustments. These volume control adjustments are preferably made 65 automatically under control of the signaling currents as indicated schematically in Fig. 1 where the volume control device 1 and the compensating volume control device 8 are controlled by operation of a control circuit 9 which in 70 turn is controlled by the signaling current di- 75
- verted from the path EA by the forward-acting control circuit 10 connected to the input of the device 1 and the backward-acting control circuit 11 connected to the output of the control device 1, and where the volume control device 5 and the compensating volume control device 4 at station B are controlled by control circuit 12 which is controlled in turn by signaling current diverted from the path WA by the control circuits 13 and 14 respectively connected to the input and output of the volume control device 5 in the path WA. These automatic volume control systems, for example, may be of the type disclosed in the Patent No. 1,853,070 issued to D. Mitchell, April 19, 1930, and Patent No. 1,853,974 issued to Hogg et al, April 12, 1932, in which three-electrode space discharge amplifying devices are utilized as loss elements in the signal transmission paths and the potentials on the grids of these devices are automatically controlled by adjusting the charge on condensers in the grid circuits, in accordance with the volume level of the signals in said paths to adjust the gain of the space discharge devices in proper manner.
- The modulators M_1 and M_2 , and the demodulators DM_1 and DM_2 may be of any of the well-known types, for example, vacuum tube modulators and demodulators as disclosed in Carson Patent No. 1,343,308, issued June 15, 1920. The modulators are supplied with carrier currents of a given frequency from the associated oscillators O_1 and O_3 , which may be of any suitable character, and are so arranged that normally the carrier frequency is suppressed, but when the band of modulating current frequencies, that is, the signaling current received from the telephone circuit L_1 or L_2 , is supplied to the modulator the carrier frequency is modulated by the modulator so that a double band of frequencies appears in the output circuit of the modulator. The band filters 2 and 6 in the output of modulators M_1 and M_2 respectively, are preferably of the general type disclosed in U. S. patents to George A. Campbell No. 1,227,113 and No. 1,227,114, issued May 22, 1917. These filters may be so designed as to transmit one of the side bands, preferably the upper, and to suppress the other, so that the modulator in conjunction with the band filter, operates to step up the band of speech frequencies supplied to the modulator to a band of equal width, but of carrier frequencies. The band filter 3 in the input of the demodulator DM_1 at station B in the transmission path EA is similar to the band pass filter 2 at station A, and may be arranged to transmit the same band of frequencies. Similarly, the band pass filter 7 at station A in the transmission path WA is similar to the band pass filter 6 at station B in the same path, and may be arranged to transmit the same band of frequencies.
- The demodulator DM_1 at station B in the transmission path EA, and the demodulator DM_2 at station A in the transmission path WA, which are preferably vacuum tube demodulators of the type disclosed in the above mentioned Carson patent, operate when supplied with carrier current from the associated carrier frequency oscillator O_2 or O_4 and with the band of modulated signaling current from the output of the band pass filter 3 or 7, to combine these frequencies so as to produce in the output of each demodulator a band of signaling frequencies corresponding to the band of signaling fre-

quencies impressed upon the modulator at the transmitting end of the system.

A terminal echo suppressor of the "sender" type is associated with the four-wire cable circuit at each terminal station, forming the carrier channels for opposite directions. The unit at each station comprises a suppressor portion responsive to signals in the outgoing two-wire circuit to disable the incoming two-wire circuit, and another portion, which may be referred to as the "interlocker", which is responsive to signals in the incoming two-wire circuit to disable the suppressor portion of the unit. Thus, the suppressor portion of the "sender" type terminal echo suppressor at station A, illustrated in Fig. 1, comprises a control circuit 15 having its input connected across the path EA in the input of the modulator M₁ therein, and comprising a delay circuit 16, a signal-controlled, relay-controlling device 17, which may be a vacuum tube, amplifier-rectifier circuit of the type well-known in the art, and the winding of a mechanical relay 18 connected across the output of the device 17. The normally closed switch contacts 19 in the transmission path WA in the output of the demodulator DM₂ therein are adapted to be opened by operation of the relay 18, so as to disable the output of the east to west transmission path WA.

The "interlocker" portion of the "sender" type terminal echo suppressor at station A comprises a control circuit 20 having its input connected across the east to west transmission path WA between the disabling point therein and the input of the compensating volume control device 8, and comprising a delay circuit 21, a signal-controlled, relay-controlling device 22 similar to the device 17, and the windings of mechanical relays 23, 24 and 25 connected in parallel across the output of the device 22. The normally closed switch contacts 26 in the output of the control circuit 15 are adapted to be opened in response to operation of the mechanical relay 23, to disable the mechanical relay 18 in the suppressor circuit. The normally closed switch contacts 27 and 28 in the circuits connecting the control circuit 9 of the automatic volume control system to the volume control device 4 in the path EA and the compensating volume control device 8 in the path WA, respectively, are adapted to be opened in response to operation of relays 24 and 25, to prevent false operation of the automatic volume control system at station A in response to current in the transmission path EA when signal transmission is taking place in the direction from east to west over the transmission path WA.

Similarly, the "sender" type of terminal echo suppressor located at station B comprises a suppressor portion and an "interlocker" portion. The suppressor portion comprises a control circuit 29 having its input connected across the east to west transmission path WA in the input of the modulator M₂ therein, and comprising a delay circuit 30, a signal-controlled, relay-controlling device 31, similar to the devices 17 and 22, and the winding of mechanical relay 32 connected across the output of the device 31. The normally closed switch contacts 33 in path EA located between the output of the demodulator DM₁ and the compensating volume control device 4 therein are adapted to be opened by operation of the mechanical relay 32 when its winding is energized in response to operation

of the control device 31, to disable the output of the transmission path EA.

The "interlocker" portion of the "sender" type terminal echo suppressor located at station B comprises a control circuit 34 having its input connected across the path EA between the disabling point therein and the compensating volume control device 4 and comprising a delay circuit 35, a signal-controlled, relay-controlling device 36, similar to the devices 17, 22 and 31, 10 and the windings of the mechanical relays 37, 38 and 39 connected in parallel to the output of the device 36. The normally closed switch contacts 40 in the output of the control circuit 29 are adapted to be opened by operation of the relay 37 in response to energization of its winding by operation of the control device 36, to disable the input of the mechanical relay 32 in the suppressor portion of the terminal echo suppressor unit at station B. The normally closed switch contacts 41 and 42 in the circuits connecting the control circuit 12 of the automatic volume control system at station B to the volume control device 5 in the path WA and the compensating volume control device 4 in the path EA, respectively, are adapted to be opened in response to operation of relays 38 and 39, to prevent false operation of the automatic volume control system in response to current in the path WA when signals are being transmitted over the west to east transmission path EA.

As indicated in the drawing, the system of Fig. 1 may comprise other carrier channels C₁, C₂ for transmitting other conversations in the direction from west to east and other carrier channels C₃, C₄ for transmitting other conversations in the direction from east to west, between the telephone lines L₁ and L₂. These additional carrier channels will contain apparatus identical with that in the channels which have been illustrated in detail except that the carrier oscillator for each channel will be designed to generate a different carrier frequency requiring that the band filters associated with the modulator and demodulator in each channel have different transmission ranges than the similar filters in the other channels, this range being determined by the particular carrier frequency assigned to that channel.

The delay circuits 16 and 21 at station A and the delay circuits 30 and 35 at station B may be networks of any type suitable for producing a delay in the transmission therethrough of alternating current waves impressed on their inputs, for example they may be low pass electrical filters such as disclosed in U. S. patents to Campbell, Nos. 1,227,113 and 1,227,114, issued May 22, 1917, or networks for a similar purpose such as disclosed in Arnold Patent No. 1,565,302, issued December 15, 1925. The delay circuit 16 in the control path 15 at station A, and the delay circuit 30 in the control circuit 29 at station B are utilized to provide a given amount of delay in the operation of the suppressor circuit at the terminal in response to the speech waves in the transmitting path thereof, to accomplish the disabling of the receiving path at the same terminal station. This delay is preferably made substantially equal to T where T is the overall transmission time of one one-way path of the four-wire circuit between the terminal stations in order that the two-wire circuit over which transmission of signals is not taking place may be disabled substantially at the same time as the signals transmitted over the other two-wire

path seize control of the switching circuit at the receiving terminal, although, as will be brought out later, under certain conditions this delay may be somewhat different. These delays in the 5 operation of the suppressors might be obtained also by making the suppressor relays 18 and 32 slow operating by suitable mechanical design, in which case the delay circuits 16 and 30 would not be required.

10 In the case where the delay time in operation of the suppressor is made equal to T, which is preferable, substantially no time delay in the operation of the "interlockers", i. e. the control circuits 28 and 34, will be required. Hence the 15 delay circuit 21 in control circuit 28 and the delay circuit 35 in control circuit 34 may be omitted. However, where the delay times of the 20 delay circuits 16 and 36 in the suppressor circuits at the respective terminal stations are greater than T, which will be the case in an alternative method of operation to be described below, the delay circuits 21 and 35, or a suitable 25 design of the interlocker relays 23 and 37 to make them sufficiently slow operating, will be required to give the proper time delays in the operation of the interlockers.

In the preferred case, the control circuit 15 controlling the disabling of the transmission path WA, and the control circuit 29 controlling the 30 disabling of the transmission path EA should be designed to have suitable hang-over times in their operation so as to remain operated to maintain the controlled transmission path disabled a given time after the supply of speech current to the control device 17 in control circuit 15, or to the control device 31 in control circuit 29 ceases. These hang-over times in the 35 operation of the echo suppressors may be obtained by suitable mechanical design of the 40 mechanical relays 18 and 32 to make them slow releasing to the required degree, or by any other suitable means. In the preferable case, the 45 hang-over time of each of these relays will be made equal to T, although, as will be brought out later, under certain conditions, these hang-over times may be made less than T. Preferably, the interlocker circuits, i. e. control circuit 28 at station A and control circuit 34 at station B are designed to have suitable hang-overs in 50 their operation to prevent the echo suppressors and the automatic volume control circuits at the terminal stations from being prematurely made operative after they have been disabled, when the supply of speech waves to control circuits 28 and 34 respectively, ceases. As in the case 55 of the echo suppressor circuits, these hang-over times in the operation of the "interlockers" may be produced by suitable design of the mechanical relays 23, 24 and 25 at station A and the mechanical relays 37, 38 and 39 at station B to 60 make them slow releasing to the required degree. These hang-over times in the preferable case are made equal to T, although, as will be brought out later, under certain conditions these hang-over times will be made larger than T.

The operation of the system of Fig. 1 will now be described. It will be assumed that speech waves for transmission from west to east are being received over the two-wire circuit L₁, and, at that time, no speech waves for transmission from east to west are being received at station B over the two-wire circuit L₂.

The speech waves will be impressed by the hybrid coil H₁ upon the input of the transmission path EA and transmitted thereover toward

the modulator M₁. A portion of these speech waves is diverted from the path EA in the input of the volume control device 1 by control circuit 10, and another portion is diverted from the path EA in the output of the volume control device 1 by control circuit 11, these two portions being impressed upon the control circuit 9 causing its operation in suitable manner to adjust the volume control device 1 in the path EA so as to maintain the speech waves in its 10 output at a substantially constant volume level, and to adjust the compensating volume control device 3 in the path WA in inverse manner so as to insure that the transmission equivalent around the loop comprising paths EA and WA 15 is not changed by the adjustment of the volume control device 1. The main portion of the speech waves in the output of the volume control device 1 then is impressed upon the input of the modulator M₁. A small portion, however, of the speech waves in the output of the volume control device 1 is diverted into the control circuit 15 and after being delayed in transmission through delay circuit 16 for a time T is impressed on the control device 17 causing 20 its operation to energize the winding of the echo suppressor relay 18 in its output.

Relay 18 will then operate, and will be maintained operated as long as the speech waves are being substantially continuously impressed upon the control device 17 and for an additional 30 hang-over interval of T, to open the normally closed switch contacts 19 in the transmission path WA in the output of the demodulator DM₂ therein, thereby rendering that path inoperative thereafter to transmit later received waves to the input of the interlocker circuit 28 or to the two-wire circuit L₁ from the output of the path WA.

The speech waves impressed upon the input 40 of the modulator M₁ in the path EA will meanwhile be combined therein with the carrier frequencies from the oscillator O₁ to form combination waves in the output of the modulator. Of these combination waves one band is selected 45 by the band pass filter 2 and transmitted out over the path EA to the distant station B where it is selected by the band pass filter 3 and impressed upon the input of the demodulator DM₁ at that station. These waves are combined in 50 the demodulator DM₁ with the carrier frequency from the oscillator O₂ producing in the output of the demodulator a band of speech frequencies corresponding to the band impressed upon the modulator M₁ at station A. The main portion 55 of this band of speech frequencies will be transmitted through volume control compensating device 4 and will be impressed on the two-way telephone circuit L₂ by hybrid coil H₂, over which circuit it will be transmitted to the listening subscriber associated therewith. A small portion of the speech waves in the output of the demodulator DM₁ in the path EA will be diverted into the input of the control circuit 34 60 and, the delay circuit 35 having been omitted in the case being considered, will cause immediate operation of the control device 36 to energize the windings of mechanical relays 37, 38 and 39 connected to the output thereof.

Relay 37 will operate immediately to open the normally closed switch contacts 40 in the output of control circuit 29 thereby preventing subsequent operation of the control device 31 in response to speech waves from the path WA from 75

causing false operation of the relay 32 to block the path EA.

Relays 33 and 39 will operate substantially simultaneously with relay 37 to open the normally closed switch contacts 42 and 41 in the output circuit of control circuit 12 of the automatic volume control system thereby preventing subsequent false operation of that system by waves subsequently received by path WA from the circuit L₂ or by unbalance currents from the path EA transmitted through the hybrid coil H₂.

The speech currents of the west subscriber associated with the telephone circuit L₁ have now obtained complete control of the switching circuits at both stations A and B.

Now let it be supposed that the east subscriber associated with the telephone circuit L₂ starts to talk but slightly after the west subscriber associated with the telephone circuit L₁ has started to talk. It is apparent that the east subscriber will not be able to get his speech current through to the west subscriber associated with L₁ because the path WA has been previously open-circuited at station A by the opening of switch contacts 49 in response to the previous operation of control device 17 by the first talker's speech current. It will also be apparent that the east subscriber associated with the circuit L₂, if he starts talking after the west subscriber associated with the circuit L₁ will not be able to seize control of the switching circuit at station B away from the first talker because the output of the control circuit 29 will have been disabled by the opening of switch contacts 40 in response to the first talker's speech current before the second talker can get his speech current through to the suppressor relay 32 because of the delay of T introduced by the delay circuit 30 in the control circuit 29.

Now let it be supposed that the west subscriber associated with the circuit L₁ ceases to talk. Because of the delay of T introduced by the delay circuit 16 in control circuit 15 at station A and of the delay of T in the transmission of the west subscriber's speech current over the path EA to station B, the control device 17 in control circuit 15 and the control device 36 in control circuit 34 at station B will remain operated for the time T after the first talker's speech current ceases to arrive at station A over the circuit L₁. At the end of this interval of time control device 17 in control circuit 15 and control device 36 in control circuit 34 will release substantially simultaneously and the winding of echo suppressor relay 18 at station A and the windings of interlocker relays 37, 38 and 39 at station B will consequently be deenergized. However, because these relays are designed to have a hang-over of T, it will be apparent that the switching circuits at both terminals will remain in the operated condition initiated by the first talker's speech current for an additional interval of T. Thus, it is evident that the second talker cannot break in and seize control of the switching circuits away from the first talker unless the pause in the continuous transmission of the first talker's speech current exceeds 2T. At the end of this interval the switching circuits will return to their normal inactive positions indicated in Fig. 1, and control of these circuits thereafter may be seized by the subscriber first starting to talk.

The operation of the system for the case where the east subscriber associated with the circuit L₂

starts to talk before the west subscriber associated with the circuit L₁ will be clear from the above description of the converse condition.

By changing the amount of delay and hang-over in the operation of the echo suppressor and interlocker circuits, the operation of the system a to what happens to the second talker's speech may be changed. For example, if the delay circuits 16 and 36 in control circuits 15 and 29, respectively, are designed to introduce a delay of 10 2T instead of T, the delay circuits 21 and 35 in interlocker control circuits 20 and 34, respectively, are designed to have a delay of T instead of O, the hang-over times of echo suppressor relays 18 and 32 in control circuits 15 and 29, 15 respectively, are made O instead of equal to T, and the hang-over times of the interlocker relays 23, 24 and 25 in control circuit 20 and interlocker relays 31, 38 and 39 in control circuit 34 are made equal to T, then with the circuit in- 20 active, when one party starts talking and the other immediately afterwards the second speaker's speech current will partially get through to the first speaker. If the circuit is active and the listener says something immediately on per- 25 ceiving a pause by the talker, the listener's speech current will partially get through to the talker.

In still another case the delay circuits 16 and 30 in control circuits 15 and 29, respectively, 30 would be designed so that the echo suppressors will be delayed in operation for a time of 2T, the echo suppressor relays 18 and 32 would be designed to have substantially O hang-over in operation, the delay circuits 21 and 35 in the control circuits 20 and 34, respectively, would be omitted so that there will be substantially no delay in the operation of the interlockers, and the hang-over times of the interlocker relays 23 and 31 would be made substantially O. In 40 the latter case, whether the circuit is inactive or active, when one party starts talking and the other starts talking immediately afterwards, the speech currents of both parties will get through to the other party, but there will be no 45 echo suppression.

The "sender" terminal echo suppressor circuits illustrated in Fig. 1 are applicable as well to long four-wire voice frequency telephone systems as well as to the carrier system as de- 50 scribed. The system for voice frequency opera- 55 tion will be the same as illustrated in Fig. 1 except that the modulators and associated oscillators and band pass filters will be left out. The operation would be similar to that just described.

Fig. 2 shows one carrier channel for each direction of a four-wire carrier telephone circuit employing automatic volume control and "receiver" terminal echo suppressors. Except for the echo suppressor circuits, the system of Fig. 2 60 is identical with that of Fig. 1. The apparatus in the identical portions of the systems of Fig. 1 and Fig. 2 bear the same identification characters.

As in the case of the "sender" type of terminal echo suppressor described in connection with Fig. 1, the "receiver" type of terminal echo suppressor located at each terminal station A and B of the system of Fig. 1, comprises a suppressor portion and an "interlocker" por- 70 tion.

The suppressor portion of the "receiver" type terminal echo suppressor located at station A in the system of Fig. 2 comprises a control circuits 43 having its input connected across the 75

path WA in the output of the demodulator DM₂ therein, and comprising a signal-controlled, relay-controlling device 44, similar to the device 17 in the system of Fig. 1, and the windings of 5 mechanical relays 45 and 46 connected in parallel to the output of the device 44. The "interlocker" portion of the "receiver" type terminal echo suppressor at station A comprises a control circuit 47 having its input connected across the path EA in the input of the modulator M₁ and comprising a delay circuit 48, a signal-controlled, relay-controlling device 49, similar to the device 44, and the winding of a 10 mechanical relay 50 connected across the output 15 of the device 49. The normally closed switch contacts 51 in the input of the circuit EA are adapted to be opened by operation of echo suppressor relay 45 in response to energization of its winding by operation of the control device 20 44 in response to signaling current impressed upon the input of the control circuit 43 from the path WA, thereby disabling the input of the path EA. The normally closed switch contacts 25 52 in the output of the control circuit 47 are adapted to be opened by operation of the relay 46 also in response to the operation of the control device 44, thereby preventing false operation of the relay 50 in response to subsequent operation of the control device 49 in control circuit 30 47. The normally closed switch contacts 53 in the output of the control circuit 43 are adapted to be opened by the mechanical relay 50 when its winding is energized by operation of the control device 49 in response to signals impressed 35 upon the input of the control circuit 47 from the path EA.

The suppressor portion of the "receiver" type terminal echo suppressor located at station B comprises a control circuit 54 having its input connected across the path EA in the output of the demodulator DM₁ therein and comprising a signal-controlled, relay-controlling device 55, similar to the device 44, and windings of 40 mechanical relays 57 and 56 connected in parallel 45 across the output of the device 54. The "interlocker" portion of the echo suppressor at station B comprises a control circuit 58 having its input connected across the path WA at a point therein between the output of the volume 50 control device 5 and the input of the modulator M₂, and comprising a delay circuit 59, a signal-controlled, relay-controlling device 60, and the winding of a mechanical relay 61 connected to the output of the device 60.

55 The normally closed switch contacts 62 located in the input of the path WA between the hybrid coil H₂ and the input of the volume control device 5 therein are adapted to be opened by the relay 56 when its winding is energized 60 by operation of the control device 55 in response to signal waves impressed upon the input of the control circuit 54.

The normally closed switch contacts 63 in the output of the control circuit 58 are adapted 65 to be opened by mechanical relay 57 when its winding is energized by operation of the control device 55 in response to signaling waves impressed upon the input of the control circuit 54 from the path EA, thereby preventing 70 false operation of relay 61 in response to subsequent operation of control device 60 by waves received from the path WA.

The normally closed switch contacts 64 in the output of the control circuit 54 are adapted to 75 be opened by mechanical relay 61 when its wind-

ing is energized by operation of the control device 60 in response to signals impressed upon the input of the control circuit 58 from the path WA, thereby preventing false operation of the relays 57 and 56 by subsequent operation of the control device 55 in response to waves from the path EA. 5

The operation of the system of Fig. 2 will now be described. It will be assumed that speech waves for transmission from west to east are 10 being received over the two-wire circuit L₁, and, at that time, no speech waves for transmission from east to west are being received at station B over two-wire circuit L₂.

The speech waves will be impressed by the 15 hybrid coil H₁ upon the input of the transmission path EA and transmitted thereover to the volume control device 1. A portion of these speech waves is diverted from the path EA in the input of the volume control device 1 by control circuit 10, and another portion is diverted from the path EA in the output of the volume control device 1 by control circuit 11, these two portions being impressed upon the control circuit 9 causing its operation in suitable manner 20 to adjust the volume control device 1 in the path EA so as to maintain the speech waves in its output at a substantially constant level, and to adjust the compensating volume control device 8 in the path WA in inverse manner 30 to insure that the transmission equivalent around the loop comprising paths EA and WA is not changed by the adjustment of the volume control device 1. The speech waves in the output of the volume control device 1 are divided between the input of the modulator M₁ and the input of the control circuit 47. The portion diverted into control circuit 47 after being delayed in the delay circuit 48 for a desired interval of time, which is preferably equal to T, 40 is impressed upon the control device 49 causing its operation to energize the winding of relay 50 in its output. 35

Relay 50 will then operate, and will be maintained operated as long as the speech waves are 45 being substantially continuously impressed upon the control device 49 and for an additional hang-over interval preferably of T, to open and maintain opened the normally closed switch contacts 53 in the output of the control circuit 50 43, thereby preventing operation of the echo suppressor relays 45 and 46 due to subsequent operation of the control device 44 by the signal waves received from the path WA.

Meanwhile, the main portion of the speech 55 waves impressed upon the input of the modulator M₁ in the transmission path EA will be combined therein with the carrier frequency from the associated carrier frequency oscillator O₁ to form combination modulated waves in the 60 output of the modulator. Of these combination waves, one frequency band is selected by the band pass filter 2 and transmitted out over the path EA to the distant station B where it is selected by the band pass filter 3 and impressed 65 upon the input of the demodulator DM₁ at that station. The impressed waves are combined in the demodulator DM₁ with the carrier frequency from oscillator O₂ producing in the output of the demodulator a band of speech frequencies corresponding to the band impressed upon the modulator M₁ at station A. This band in the 70 output of the demodulator DM₁ will be divided between the input of the compensating volume control device 4 in the transmission path EA 75

and the input of the control circuit 54 comprising the suppressor portion of the "receiver" type terminal echo suppressor at station B. The main portion of the speech waves will be transmitted through the compensating volume control device 4 and will be impressed on the two-way telephone circuit L_2 by hybrid coil H_2 , over which circuit it will be transmitted to the listening subscriber associated therewith.

10 Meanwhile, the portion of the speech waves diverted into control circuit 54 will cause the operation of the control device 55 therein to energize the windings of the mechanical relays 56 and 57 connected to its output. Relay 56 15 will operate immediately to open the normally closed switch contacts 62 in the input of the path WA thereby rendering that path inoperative thereafter to transmit waves from the telephone line L_1 thereafter received to the subscriber associated with the circuit L_1 , to the input of the volume control circuit 42, or to the input of the control circuit 58.

The speech currents of the west subscriber associated with the circuit L_1 have now obtained 25 complete control of the switching circuits at both stations A and B. Because of the delay of T , equivalent to the transmission time between the station A and the station B over the one-way path EA, introduced by the delay circuit 48 in the control circuit 47 at station A, the operation of the interlocker relay 50 to disable the suppressor circuit at station A occurs substantially at the same time as the operation of the echo suppressor relays 56 and 57 at station B.

30 Now let it be supposed that the east subscriber associated with the telephone circuit L_2 starts to talk after the west subscriber associated with the telephone circuit L_1 has started to talk. If the east subscriber starts to talk soon enough after the west subscriber has started to talk, a small part of the east subscriber's speech current may get through to the west subscriber because of the delay in operation of the echo suppressor relay 56 under control of 35 the west subscriber's speech current due to the time of transmission over the path EA. However, this small part of the east subscriber's speech current which will get through before the relay 56 has operated to open-circuit the input 40 of the path WA by opening switch contacts 62 cannot seize control of the switching circuits at either station B or station A away from the west subscriber because, on account of the delay of T introduced by the delay circuit 59 in control circuit 58 in these currents and the delay of T required for transmission of these currents from station B to station A over the path WA, the echo suppressor relay 57 will have operated 45 to block the output of the control circuit 58 and the interlocker relay 50 in the control circuit 47 at station A will have operated to block the output of control circuit 43 before the east subscriber's speech current will have passed the disabling points in the two circuits 58 and 43.

50 If the east subscriber associated with the circuit L_2 starts to talk a sufficiently long time after the west subscriber associated with the circuit L_1 to enable the west subscriber's speech current to have previously operated echo suppressor relay 56 to open-circuit the input of the path WA it is apparent that none of the east subscriber's speech current will be transmitted to the west subscriber.

The echo suppressor relays 45 and 46 in the 55 suppressor circuit at station A, and the echo

suppressor relays 56 and 57 in the suppressor circuit at station B, preferably are designed to have substantially O hang-over in their operation so that they will release substantially instantaneously with cessation of supply of speech current to the control device 44 and the control device 55, respectively, thus enabling the listener to get a portion of his speech current through in an appreciable pause in the continuous conversation of the first talker. The interlocker relay 50 in the control circuit 47 at station A and the interlocker relay 61 in the control circuit 58 at station B are preferably designed to have a hang-over in their operation, by any suitable means, of substantially T so that when the talking subscriber stops talking, these relays will remain operated for the additional interval of time T after the supply of the first talker's speech current to the control devices 48 and 60, respectively, falls off, thus preventing loss of any part of the first talker's speech current by premature operation of the control devices by the second talker's speech current.

By changing the amount of delay and hang-over in the operation of the interlocker circuits 47 and 58 in the system of Fig. 2, the operation of the system as regards what happens to the second talker's speech current may be changed. If the delay introduced in the interlocker control circuits 47 and 58 is reduced from T to substantially O delay time, as by omitting the delay circuits 49 and 59, and the hang-over time of each interlocker relay 50 and 61 is changed to $2T$ from T , and if the two subscribers at opposite ends of the system both start talking within a time interval of T , where T is the transmission time between stations A and B, the speech currents of both will get through to the other subscriber, but there will be no echo suppression as the interlocker circuits controlled by each subscriber will disable the echo suppressor circuit controlled by the other subscriber before the latter's speech current can make it operative.

It will be noted that in the system of Fig. 2 the disabling points in each of the one-way transmission paths EA and WA are located in the input of that path in front of the automatic volume control device. It is apparent, therefore, that there is no possibility of false operation of the automatic volume control system caused by 50 echo currents.

The "receiver" terminal echo suppressor circuits illustrated in Fig. 2 are applicable as well to long four-wire voice frequency telephone systems as to the carrier system illustrated. The system for voice frequency operation will be the same as illustrated in Fig. 2 except that the modulators and demodulators and associated oscillators and the band pass filters will be left out.

Fig. 3 shows a long four-wire toll telephone circuit employing a "sender" terminal echo suppressor and a "receiver" terminal echo suppressor at the same terminal station. The advantage of this arrangement is that the two suppressors may be put under complete control of 65 a technical operator at one of the terminal stations.

As in the case of Fig. 1 and Fig. 2, the four-wire circuit of Fig. 3 comprises a west to east, one-way transmission path EA and an east to west, one-way transmission path WA connecting a two-way telephone circuit L_1 terminating at a west station A with a two-way telephone circuit L_2 terminating at an east station B, these paths being connected in substantially conjugate 75

relation with each other and in energy-transmitting relation with the circuits L_1 and L_2 by means of hybrid coils H_1 , H_2 and associated balancing networks N_1 and N_2 .

- 5 The "sender" type terminal echo suppressor is located at station A and comprises a suppressor portion and an interlocker portion as in the case of the system of Fig. 1. The suppressor portion comprises the control circuit 65 having its input 10 connected to the west to east transmission path EA, and comprising a delay circuit 66, a signal-controlled, relay-controlling device 67 and the windings of mechanical relays 68 and 69 connected to the output of the device 67. The interlocker portion of the terminal echo suppressor 15 comprises a control circuit 70 having its input connected across the output of the path WA at station A, and comprising a delay circuit 71, a signal-controlled, relay-controlling device 72 and the winding of mechanical relay 73 connected to the output of the device 72. Normally closed switch contacts 74 are located in 20 the transmission path WA at a point east of the input of control circuit 70, and are adapted to be opened to open-circuit the path WA by relay 68 when its winding is energized by operation of the control device 67 in response to the signal waves received from the path EA.

The normally closed switch contacts 75 in 30 the output of the control circuit 70 are adapted to be opened by the relay 69 when its winding is energized by operation of the control device 67 in response to waves from the path EA, to prevent subsequent operation of the control device 72 by waves from the path WA from producing false operation of the relay 73.

The normally closed switch contacts 76 in the output of the control circuit 65 are adapted to be opened by mechanical relay 73 when its 40 winding is energized by operation of the control device 72 in response to waves received from the path EA, to prevent subsequent operation of the control device 67 in response to waves from the path EA from causing false 45 operation of the relays 68 and 69.

As in the case of the "receiver" type of terminal echo suppressor illustrated in Fig. 2, the "receiver" type terminal echo suppressor located at station A in the system of Fig. 3 comprises 50 a suppressor portion and an interlocker portion. The suppressor portion comprises a control circuit 77 having its input connected across the output of the path WA at a point therein between the connection thereto of the control circuit 70 and the hybrid coil H_1 , and comprising a signal-controlled, relay-controlling device 78 similar to the control device 71, and the windings of mechanical relays 79 and 80 connected in parallel to the output of the control device 78. The interlocker portion of the "receiver" terminal echo suppressor comprises a control circuit 81 having its input connected across the input of the path EA between the point of connection of the control circuit 65 thereto and the hybrid coil H_1 and comprising a delay circuit 82, a signal-controlled, relay-controlling device 83 and the winding of a mechanical relay 84 connected to the output of the device 83.

In the input of the path EA between the point 70 of connection thereto of the input of control circuits 65 and 81 are the normally closed contacts 85 adapted to be opened by relay 79 when its winding is energized by operation of the control device 78 in response to waves from the path WA, to prevent waves subsequently received

over the telephone circuit L_1 from being transmitted to the telephone circuit L_2 at the station B, or to the input of the control circuits 65 and 81 at station A. In the output of the control circuit 81 are the normally closed switch contacts 86 adapted to be opened by relay 80 when its winding is energized by operation of the control device 78 in response to waves received from the path WA, to disable the input of the relay 84. In the output of the control circuit 77 are the normally closed switch contacts 87 adapted to be opened by relay 83 when its winding is energized by operation of the control device 83 in response to waves received from the path EA.

The delay circuits 66, 71 and 82 are similar to the delay circuits shown in the systems of Figs. 1 and 2. The delay circuit 66 in control circuit 65 is provided to give a delay in the operation of the suppressor portion of the "sender" 10 terminal echo suppressor at station A, of preferably 2T, 2T being the overall transmission from the point in the path EA where the input of control circuit 65 is connected thereto over the path EA through the hybrid coil H_2 and over the return path WA to the point therein where the disabling contacts 74 are located. The delay circuit 71 in control circuit 70 is provided to give a delay of preferably T in the operation of the interlocker portion of the "sender" 15 type terminal echo suppressor located at station A. The delay circuit 82 in control circuit 81 is provided to give a delay of T in the operation of the interlocker portion of the "receiver" type echo suppressor at station A. These delays in 20 the operation of the suppressors might be obtained also by making the suppressor relays 68 and 69 and the interlocker relays 73 and 84 slow operating by suitable mechanical design, in which case the delay circuits 66, 71 and 82 25 would not be required.

The control circuit 65 controlling the disabling of the path WA and the disabling of the interlocker control circuit 70, the control circuit 77 controlling the disabling of the path EA, and the control circuit 81 controlling the disabling of the control circuit 77, should, in the preferred case, that is, where the delay circuits in these control circuits have the delay times specified above, have little or no hang-over in their operation. This means that the suppressor relays 68, 79 and 80, and the interlocker relay 84 should be designed to release substantially instantaneously with cessation of supply of controlling currents to the control devices controlling their operation. In that case, the control circuit 70 should have a hang-over in its operation of substantially T, which may be obtained, for example, by making the interlocker relay 73 slow releasing to the required degree.

The operation of the system of Fig. 3 will now be described. It will be assumed that speech currents to be transmitted to station B are being received over the circuit L_1 terminating at station A, and at that time no speech currents to be transmitted from station B to station A are being received over the circuit L_2 terminating at station B.

The speech currents from circuit L_1 are impressed by hybrid coil H_1 upon the input of the 70 west to east transmission path EA and the main portion thereof will be transmitted over that path to the station B where it will be impressed by the hybrid coil H_2 on the telephone circuit L_2 over which it will be transmitted to the 75

listening subscriber. A small portion of the speech current in the path EA, however, will be diverted into the input of the control circuit 81 at station A, and another small portion will 5 be diverted into the control circuit 65 at station A. The portion diverted into control circuit 81 after being delayed in transmission through delay circuit 82 for a time of T will be impressed upon the control device 83 causing its 10 operation to energize the winding of relay 84 connected to its output. Relay 84 will operate substantially instantaneously to open the normally closed switch contacts 87 in the output of the control circuit 77 forming the suppressor 15 portion of the "receiver" type terminal echo suppressor at station A, thereby preventing subsequent operation of control device 78 in response to waves received over the path WA from causing false operation of the suppressor 20 relays 79 and 80. Because of the delay of T introduced by the delay circuit 82 in control circuit 81, control circuit 77 will be rendered inoperative substantially at the same time as the main portion of the signals transmitted over 25 the path EA reaches station B.

Meanwhile, the portion of the west subscriber's speech current diverted into control circuit 65 after being delayed in transmission through the delay circuit 66 therein for a time 30 of substantially $2T$ will be impressed on the control device 61 causing its operation to energize the windings of relays 68 and 69. Relay 68 will operate substantially instantaneously to open the normally closed switch contacts 74 in path WA rendering that path thereafter inoperative to transmit any speech currents or echo currents from the station A to the station B or to the control circuit 70 or control circuit 77. It will be seen that because of the delay of $2T$ 35 caused by delay circuit 66 in the operation of the suppressor relay 68 the path WA will remain operative to transmit to station A or control circuits 70 and 77 until the time at which the echo currents due to the west subscriber's 40 speech current would be expected to arrive at the disabling point in the path WA. Relay 69 operates substantially simultaneously with relay 68 to open normally closed contacts 75 in the output of the control circuit 70 thereby preventing subsequent operation of interlocker relay 73 by operation of control device 72 due to 45 any speech currents which may have been stored in delay circuit 71 prior to the opening of switch contacts 74 in the path WA.

The west subscriber's speech current now has 50 gained complete control of the echo suppressor circuits associated with both sides of the four-wire circuit and will maintain this control for a time of substantially $2T$ after said subscriber has ceased talking due to the delay of $2T$ introduced by delay circuit 66 in control circuit 65. At the end of an interval of T after the west subscriber has ceased talking, control device 83 in control circuit 81 releases causing relay 84 in its output to fall back returning switch contacts 87 in control circuit 77 to their normal closed condition and rendering that circuit thereafter operative in condition to be controlled by the east subscriber's speech current. A time 55 T after control circuit 77 has been rendered operative with cessation in the west subscriber's speech current, control device 67 in control circuit 65 will release causing echo suppressor relays 68 and 69 in its output to fall back returning switch contacts 74 in the path WA and

switch contacts 75 in the control circuit 70 to their normally closed condition.

If the east subscriber associated with circuit L_2 starts talking before the west subscriber associated with the circuit L_1 , the east subscriber's speech currents will be impressed upon the input of the path EA by hybrid coil H_2 and transmitted over that path to the west station A. The main portion of these speech currents will be transmitted over the output of the path WA 10 to the hybrid coil H_1 which will impress it upon the circuit L_1 over which it will be transmitted to the west subscriber. The portion of the east subscriber's speech current diverted into control circuit 70 after being delayed in transmission 15 for a time interval of T while passing through the delay circuit 71 will cause the control device 72 to be operated to energize the winding of interlocker relay 73. Interlocker relay 73 will then operate to open the normally 20 closed switch contacts 76 disabling the echo suppressor controlled from the path EA by the west subscriber's speech current. Another portion of the east subscriber's speech current will be diverted into control circuit 77 causing the 25 operation of control device 78 therein to energize the windings of echo suppressor relays 79 and 80. Echo suppressor relay 79 will operate to open normally closed switch contacts 85 in the input of the path EA making that path inoperative to transmit the west subscriber's speech current to station B or to the input of control circuits 65 and 81. Relay 80 will operate simultaneously with relay 79 to open normally 30 closed switch contacts 86 in the output of control circuit 81 to disable the input of interlocker relay 84, thus preventing subsequent operation of the control device 83 by the west subscriber's speech energy transmitted to the control circuit 81 before switch contacts 85 in 35 the input of the path EA have been opened, from causing false operation of interlocker relay 84.

If the west subscriber starts talking after the east subscriber starts talking but within a time interval of T, it will be apparent that the portion of his speech current passing switch contacts 85 in the input of the path EA before these contacts have been opened by operation of echo suppressor relay 79 will be transmitted over the path EA to the east subscriber associated with L_2 . The portion of these currents diverted into control circuit 81, however, because of the delay introduced by delay circuit 82 therein, will not cause false operation of interlocker relay 84 because of the previous operation of echo suppressor relay 80 to block the input of relay 84. The portion of the west subscriber's speech current diverted into control circuit 65, because of the delay introduced therein by delay circuit 66 will not cause false operation of echo suppressor relays 68 and 69 due to the previous operation of interlocker relay 73, to open switch contacts 76 thereby disabling the input of relays 68 and 69.

Now let it be supposed that the east subscriber associated with the circuit L_2 starts talking within the time interval T after the west subscriber associated with the telephone circuit L_1 has started talking. The east subscriber's speech current will be impressed by the hybrid coil H_2 upon the east to west transmission path WA and transmitted thereover toward the west station B. Because of the delay of $2T$ introduced 70 by the delay circuit 66 in control circuit 65 on 75

the west subscriber's speech current, it will be apparent that a portion of the east subscriber's speech current will pass by the disabling point in transmission path WA before echo suppressor relay 68 under control of the west subscriber's speech current has been operated to open the switch contacts 74 and thereby to disable the path WA. The main portion of the east subscriber's speech current passing the disabling point, i. e., the point where the switch contacts 74 are located, in the path WA will be transmitted from the output of that path to hybrid coil H₁ which will impress it upon the circuit L₁ over which it will be transmitted to the west subscriber.

A small portion of the east subscriber's speech current passing the switch contacts 74 will be diverted into the control circuit 70 and after being delayed in the delay circuit 71 therein for a time interval of T, will be impressed upon the control device 72 causing its operation. The operation of control device 72, however, will not cause false operation of relay 73 to disable the control circuit 65 because echo suppressor relay 69 has been previously operated under control of the west subscriber's speech current to disable the input of relay 73 by opening switch contacts 75.

Another portion of the east subscriber's speech current passing the switch contacts 74 in the path WA will be diverted into the control circuit 77 and will cause the operation of the control device 78 therein. The operation of the control device 78, however, will not cause false operation of echo suppressor relays 79 and 80 because relay 84 in control circuit 81 has been previously operated under control of the west subscriber's speech current to disable the input of relays 79 and 80 by opening switch contacts 87 in the output of control circuit 77. The hang-over of T in the interlocker relay 73 prevents false operation of echo suppressor relays 68 and 69 under control of the west subscriber's speech current until after all of the east subscriber's speech current has been transmitted to the circuit L₁.

In a modification of the circuit of Fig. 3, the delay circuit 66 in control circuit 65 would be designed to give a delay of T instead of 2T and the hang-over of echo suppressor relays 68 and 69 would be made substantially T instead of 0 and the delay in control circuit 70 would be substantially eliminated by omitting the delay circuit 71.

It is apparent that in the system of Fig. 3, both of the echo suppressors need not be located at one terminal as shown, but that the "sender" type echo suppressor may be located at one terminal station and the "receiver" type terminal echo suppressor located at the other terminal, or that either one may be located at a midpoint and the other located at either one of the terminals in which case the delays introduced into the control circuit and the hang-over times of the suppressor and interlocker relays may be somewhat different from the values indicated in Fig. 3. The echo suppressor system of Fig. 3 may, of course, be applied to a multiplex carrier telephone circuit similar to those shown in Figs. 1 and 2.

Although the invention has been described in connection with four-wire circuits employing continuous two-wire paths for transmission in either direction between terminal stations, it is apparent that the principles of the invention apply equally well to circuits employing short

sections of two-wire lines for transmitting and receiving at each terminal station, respectively, and employing as an intermediate link a long two-way transmission medium, such as the air link of a two-way radio telephone circuit or the submarine cable link of a two-way submarine cable telephone circuit.

Although in the particular embodiments of the invention illustrated and described mechanical relays have been shown for conditioning the transmission paths by operating movable switches to close or open-circuit the paths, the invention is not limited to circuits employing the particular conditioning means shown. For example, within the scope of the invention the transmission paths may be effectively disabled by short-circuits or loss networks inserted in the paths, controlled by relays. Stationary devices having no movable elements may be employed in place of the mechanical relays shown, for example, vacuum tube relays, such as disclosed in Crisson Patent 1,647,212, issued November 1, 1926, or in the article by C. A. Beer and C. T. Evans in the Institute of P. O. Electrical Engineers (London), vol. 20, pp. 65 to 72 inclusive, published in 1920.

What is claimed is:

1. In a two-way signal transmission system comprising at least near the terminals thereof normally operative one-way paths for transmitting signals in opposite directions, means connected to the outgoing one-way path near at least one terminal of the system, and responsive to outgoing signals therein to disable the incoming path at the same terminal substantially at the same time as the arrival of said outgoing signals at the other terminal of the system, and means connected to the incoming path near said one terminal, and responsive substantially immediately to incoming signals therein to disable the output of the incoming path-disabling means at the same terminal.

2. In a two-way signal transmission system comprising one-way paths for transmitting signals in opposite directions between distant stations, means at each station connected to the outgoing one-way path thereat and responsive to outgoing signals therein to disable effectively the incoming one-way path at the same station substantially at the same time as the arrival of said outgoing signals at the distant station, and means at each station connected to the incoming one-way path thereat and responsive to incoming signals therein to disable substantially immediately the incoming path-disabling means in its output at the same station.

3. In a two-way signal transmission system comprising normally operative one-way paths for transmitting signals in opposite directions between widely separated stations, means at each station responsive to signals in the outgoing one-way path thereat to disable effectively the incoming one-way path at the same station substantially at the time of arrival of said signals at the distant station, means at each station responsive substantially immediately to incoming signals in the incoming path thereat to disable the incoming path-disabling means at the same station in its output, and means at each station for maintaining said incoming path-disabling means disabled after cessation of said incoming signals thereat for a time substantially equal to the transmission time between stations over one of said one-way paths.

4. In a two-way signal transmission system

comprising normally operative one-way paths for transmitting signals in opposite directions between widely separated stations, means at each station responsive to signals in the outgoing one-way path thereat to disable effectively the incoming one-way path at the same station substantially at the time of arrival of said signals at the distant station, means at each station responsive substantially immediately to incoming signals in the incoming path thereat to disable the incoming path-disabling means at the same station, and means at each station for maintaining the incoming path disabled after cessation of said outgoing signals for a time substantially equal to the transmission time between said stations over one of said one-way paths.

5. A two-way signal transmission system comprising a four-wire circuit connecting terminals and consisting of two oppositely-directed one-way signal transmission paths which are normally operative, means at one terminal only of said medium connected to the transmitting path thereat and responsive to signals therein to disable the receiving path at said one terminal substantially at the time of arrival of the transmitted signals at the distant terminal, means at said one terminal only connected to the receiving path thereat and responsive to signals therein to disable substantially immediately the receiving path-disabling means at said one terminal in its output, means at said one terminal connected to the transmitting path thereat and responsive to signals therein to disable the transmitting path-disabling means at said one terminal substantially at the time of arrival of the transmitted signals at the distant terminal, and means at said one terminal responsive to operation of the transmitting path-disabling means thereat to prevent the disabling thereof thereafter in response to signals in the transmitting path at said one terminal.

6. In a two-way signaling system comprising at least near the terminals thereof one-way paths for signal transmission in opposite directions, means near at least one terminal of the system connected to the outgoing path thereat and responsive to outgoing signals therein for automatically controlling the amplification in said one-way paths, means near said one terminal

connected to the outgoing path thereat and responsive to outgoing signals therein to disable the incoming path at the same terminal, and means near said one terminal connected to the incoming path thereat, and responsive to incoming signals to disable the incoming path-disabling means and said amplification-controlling means while maintaining said outgoing path operative to transmit outgoing signals.

7. In a two-way signal transmission system comprising at least near the terminals thereof normally operative one-way paths for signal transmission in opposite directions, means near one terminal of the system connected to the outgoing path thereat and responsive to outgoing signals therein to automatically control the amplification in said one-way paths, means connected to the incoming path near said one terminal and responsive to incoming signals therein to disable the amplification-controlling means at the same terminal while allowing transmission of outgoing signals over said outgoing path thereat, means near said one terminal connected to the outgoing path thereat and responsive to outgoing signals therein to disable the incoming path and the amplification-control disabling means at said one terminal, and means also responsive to the incoming signals in the incoming path near said one terminal when said incoming path is operative to disable the means responsive to outgoing signals for disabling said incoming path and said amplification control-disabling means.

8. In a two-way signal transmission system comprising at least near the terminals thereof normally operative one-way paths respectively for transmitting incoming and outgoing signals, means connected to the outgoing one-way path near at least one terminal of the system, and responsive to outgoing signals therein to disable the incoming path at the same terminal, means for delaying the disabling of said incoming path in response to said outgoing signals for a time interval substantially equal to the signal transmission time between the terminals of said system, and means connected to the output of the incoming path at said one terminal beyond the disabling point in that path, and responsive substantially immediately to incoming signals in said incoming path when it is operative, to disable said incoming path-disabling means in its output.
